UNITED STATES PATENT OFFICE.

PAUL VICTOR RITSCHARD, OF RIVERTON, NEW JERSEY, ASSIGNOR TO THE KEYSTONE WATCH CASE COMPANY, OF RIVERSIDE, NEW JERSEY, A CORPORATION OF PENNSYLVANIA.

DESIGN FOR A WATCHCASE BOW.

Application filed July 3, 1925. Serial No. 13,985. Term of patent 14 years.

To all whom it may concern:

Be it known that I, PAUL VICTOR RITSCHARD, a citizen of the United States of America, residing at Riverton, in the county of Burlington and State of New Jersey, have invented a new, original, and ornamental Design for Watchcase Bow, reference being had to the accompanying drawing, forming a part thereof.

In the drawing, Figure 1 is a perspective view of my new design for a watchcase bow, and Figure 2 is a side view thereof.

I claim:
The ornamental design for watchcase bow as shown.

PAUL VICTOR RITSCHARD.
